UNITED STATES PATENT OFFICE.

LOUIS PELOQUIN, OF SOUTHBRIDGE, MASSACHUSETTS.

MEANS FOR SECURING TIPS TO BILLIARD-CUES.

1,029,943.

Specification of Letters Patent. Patented June 18, 1912.

Application filed March 6, 1912. Serial No. 682,041.

To all whom it may concern:

Be it known that I, LOUIS PELOQUIN, a citizen of the United States, residing at Southbridge, in the county of Worcester and State 5 of Massachusetts, have invented new and useful Improvements in Means for Securing Tips to Billiard-Cues, of which the following is a specification.

My invention relates to means for securing 10 the tips to billiard cues, that is, for applying the necessary sustained pressure thereon to cause the tips to adhere firmly. A number of devices for this purpose are on the market, but they are of the portable 15 type, that is, in use, are clamped upon the cue. In contradistinction to this type of device, my invention consists in a casing, adapted to be permanently secured to a wall, and containing spring-pressed means to exert 20 pressure on a cue while standing on the floor or on a special support.

It also comprises means adapting it for use on cues of varying lengths.

The accompanying drawing illustrates my 25 invention, Figure 1 being a front view, and Fig. 2 a side elevation, with the casing in section, of one form of the invention, Fig. 3 a front view, and Fig. 4 a side elevation of a modified form, and Fig. 5 a detail of still 30 another modification.

In Figs. 1 and 2, the casing 1, which may be either circular or rectangular in cross-section, is provided with apertured flanges or lugs 2, by which it may be secured to a 35 wall or the like 3. Slidably mounted in the casing is a piston-head or plunger 4, having a rod 5 projecting therefrom upwardly and through the casing, the end being formed into a ring 6 to form a finger-hold. A 40 strong spring 7 is connected to the underside of the plunger at one end and to the bottom of the casing at the other, whereby the plunger is normally pulled downward. Obviously, a compression spring might be 45 placed between the top of the casing and the plunger, instead. The front of the casing is provided with a longitudinal slot 8, through which passes a projection or extension 9 from the plunger, and the end of said extension 50 is enlarged to form a presser-head 10. In use, the plunger is pulled up by its rod and a billiard cue with a tip cemented

thereon is brought under the presser-head, the butt of the cue resting on the floor, and then the spring is allowed to draw the 55 plunger down and exert pressure, through the presser head, upon the cue tip for such length of time as may be necessary to cause the tip to firmly adhere. In order to be able to conveniently accommodate cues of different lengths, I may provide and have illustrated in these figures, a plurality of presser-heads at different heights. For this purpose, the extension 9 carries upwardly and downwardly extending arms 11, each of 60 which carries a presser head 12 at its end.

In Figs. 3 and 4, the extension 9 carries a vertical rod 13 at its outer end, and a plurality of sleeves 14 are rotatably mounted on said rod one above another. Each sleeve carries a presser head 15, any one of which can be brought into operative position to suit the length of cue being repaired. These figures also show a conical cup 16, secured by rods 17 to the back plate 18 of the casing, 70 to receive the butt of the cue. The back-plate is also extended upward beyond the casing and bent over to form an eye or hook 19, by which the device may be suspended or lifted. This form may or may not be 75 permanently secured to a wall by means of screws passed through the base-plate.

A further modification is illustrated in Fig. 5, in which the extension 9 carries a vertical rod provided with a series of holes 85 20, the presser-head 21 having a stem 22 to fit in any one of said holes.

Other modifications may obviously be made without departing from the invention, 90 as covered by the following claims:

1. Means for applying tips to billiard cues, comprising a casing provided with means for attachment to a wall or other vertical surface and with a slot in its front side, a downwardly spring-pressed plunger 95 therein, having an extension projecting through said slot, a presser-head mounted on the end of said projection, arms extending upwardly and downwardly from said extension and a presser head on the end of 100 each arm.

2. Means for applying tips to billiard cues, comprising a casing, having a slot in its front side, a spring-pressed plunger with-

in said casing having an extension passing through said slot, a vertical rod secured to the outer end of said extension, a series of presser heads rotatably mounted on said rod one above the other and a support for the butt of the cue connected to said casing.

5 In testimony whereof I have hereunto set

my hand in presence of two subscribing witnesses.

LOUIS PELOQUIN.
